Primary Examiner — Darlington Ly

CLAIM

The ornamental design for a chamfer tool as shown and described.

DESCRIPTION

FIG. 1 is a top, front and right side perspective view of a chamfer tool embodying my new design;

FIG. 2 is a bottom, front and left side perspective view thereof;

FIG. 3 is a top, rear and left side perspective view thereof;

FIG. 4 is a bottom, rear and right side perspective view thereof;

FIG. 5 is a front elevation view thereof;

FIG. 6 is a rear elevation view thereof;

FIG. 7 is a left side elevation view thereof;

FIG. 8 is a right side elevation view thereof;

FIG. 9 is a top plan view thereof; and,

FIG. 10 is a bottom plan view thereof.

The broken lines in the drawings are for the purpose of illustrating portions of the chamfer tool that form no part of the claimed design.

1 Claim, 10 Drawing Sheets
